CLAIM

The ornamental design for a cake shield, as shown and described.

DESCRIPTION

FIG. 1 is a front perspective view of a cake shield, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the cake shield of FIG. 1, shown in use over a cake.

The broken lines in the drawings, showing the environment of a cake and candles in FIG. 8, form no part of the claimed design.

1 Claim, 8 Drawing Sheets(56)
